UNITED STATES PATENT OFFICE.

THEODORE G. THORMODSON, OF HANSKA, MINNESOTA.

PNEUMATIC CONVEYER.

1,255,949.

Specification of Letters Patent. Patented Feb. 12, 1918.

Application filed July 2, 1914. Serial No. 848,641.

To all whom it may concern:

Be it known that I, THEODORE G. THORMODSON, citizen of the United States, residing at Hanska, in the county of Brown and State of Minnesota, have invented certain new and useful Improvements in Pneumatic Conveyers, of which the following is a specification.

This invention relates to conveyers, and 10 more particularly to that class of conveyers known as pneumatic conveyers.

The object of my invention resides in the provision of a conveyer of the above mentioned class which is provided with means 15 whereby the interior of the same may be accessible from any point throughout the length thereof.

Another object of my invention is to provide a conveyer which is formed of a plurality of interchangeable sections whereby 20 the same may be adjusted to any desired length.

A still further object of my invention is to provide a means for connecting the various 25 sections of the conveyer when it is desired to use the same.

It is a well-known fact to those skilled 30 in the art that the conveyers used at the present day are in most cases continuous throughout their length, the interior of the same being only accessible from either end, and when used in connection with fine particles of material, as in use with ensilage cutters, these small particles, being slightly 35 moistened, cling to the interior surface of the conveyer, and in time will tend to clog up and prevent the effective operation of the device, this necessitates the taking apart of the conveyer in most cases and scraping 40 the interior of the same. As has been stated hereinbefore the object of my device is to overcome the above objections and provide a means whereby access may be gained to the interior of a conveyer throughout any 45 point of its length, and that the same may be closed effectively at this point and prevent interference of the operation of the device.

The valuable feature of my invention 50 resides in the provision of a conveyer formed in the manner above set forth and consists preferably in the construction, combination and arrangement of parts hereinafter more

fully set forth in the specification and illustrated in the accompanying drawings, in 55 which:—

Figure 1 is a side elevation of a blower provided with my improved pneumatic conveyer.

Fig. 2 is a transverse sectional view taken 60 on the line 2—2 of Fig. 1.

Fig. 3 is a like view showing one of the hinged closures in open position.

Fig. 4 is a front elevation of a section of 65 my improved conveyer.

Fig. 5 is a fragmentary side elevation of 70 the same.

Similar reference characters indicate similar parts throughout the various views of the drawings.

Referring more particularly to the drawings in which the preferred embodiment of 75 my invention is illustrated, the numeral 1 indicates the casing of a blower or other air propelling device, said blower receiving its power from the belt 2 which drives the pulley 3. Said blower 1 is mounted on a base 4 which may be placed at any convenient point, the above being constructed in the conventional way and having no bearing 80 upon my invention.

In my improved conveyer I provide a plurality of tubular sections 5, each of said sections 5 being provided on their outer peripheries with angle irons 6 and 7, said angle 85 irons 6 and 7 being bolted or otherwise disposed in spaced relation upon the outer surfaces of said sections 5. For the purpose of convenience I shall describe only one of the said sections, it being understood that the 90 other sections are constructed similarly.

The said angle irons 6 and 7 disposed in spaced relation upon the sections 5 abut similar angle irons upon the adjoining section or sections and are secured together by 95 means of splice bars or plates 8, said splice bars or plates 8 being shown to advantage in Fig. 4.

To gain access to the interior of each section of the conveyer, I provide in each section an opening 9, said opening 9 being closed by a door 10, said door being preferably arcuate in contour and conforming to the configuration of the tubular conveyer sections 5. Said door 10 is provided at convenient points thereon with angle bars 11,

said angle bars 11 being of a similar configuration to the contour of the door 10. The angle bars 11 are apertured adjacent one side of the door 10 and are hinged as shown at 12 to brackets or lugs 13, said lugs 13 being bolted or otherwise secured to one of the angle bars, namely 6, said lugs 13 and angle bars 11 providing hinges upon which the door is swung.

10 The side of the door 10 which is remote from the hinged portion thereof is upturned to provide a longitudinal flange 14, said flange 14 being adapted to engage the angle bar 7 upon the section 5, when the 15 door is in a closed position, which has been shown to advantage in Figs. 2 and 4. The said up-turned flange 14 and angle bar 7 are apertured, the apertures therein being adapted to register as shown at 15 in Fig. 1, 20 and a cotterpin or other suitable securing means 16 is engaged therein, for the purpose of preventing the door 10 from accidentally opening.

From the above it will be seen that the 25 angle bars 6 and 7 perform a dual function, in that the same provides means for reinforcing the sections 5, also a means for hinging the door, and that it can be readily appreciated that they provide a simple and effective means for joining the adjacent edges 30 of the adjoining sections of the conveyer. The shape of the flange 14 and the reinforcing angle bar 7 prevent the door 10 from passing into the opening 9 below the interior surface 17 of the conveyer sections 5, 35 and forming an obstruction which would collect the finer particles of material which was being conveyed through the conveyer. As shown in Fig. 2 this door is flush with the interior surface 17, heretofore referred to, 40 thereby preventing the joint between the door and the edges of the opening 9 from forming a ridge or obstruction, collect material and prevent the effective operation of the device.

45 If it is so desired the angle bars 6 and 7 may be continued slightly beyond the marginal edges of the sections 5 on to the adjoining section, and bolted or otherwise secured thereto, this being merely an optional matter for the manufacturer of the same to decide. It will be readily understood that I do not desire to limit myself to the shape of the conveyer tube as shown in the drawings as the same may be square, hexagonal or any shape which the manufacturer desired to form the same.

From the above it will be readily appreciated by those skilled in the art that I 60 have provided a simple, cheap and effective means for attaining the objects which I have hereinbefore set forth, and that when it is desired to gain access to the interior of any one or all of the sections of my improved conveyer it is only necessary to open

one or all of the doors 10, said doors 10 being formed of such a size as to open as large a surface of each section 5 as is practicable, so that the entire interior surface of each section is practicable accessible from the exterior of the same. As is shown in Fig. 1 the conveyer tubes 5 are secured to a neck 2' which extends tangentially from the blower 1 and serves as a means for connecting the conveyer with the blower.

If it is so desired the sections 5 of the conveyer may be made in such a manner as to allow the adjoining ends of the two sections to overlap or engage by slipping one within the other, and then securing the same by the angle irons 6 and 7 and the plates 8, however, the manner in which the adjoining marginal edges of these sections are connected is a matter which will be determined in practical fields, and which has no bearing upon the invention as now set forth, the only feature of said joining means is the provision of the angle irons 6 and 7 and the plate 8.

From the above description taken in connection with the accompanying drawings it is thought that a thorough understanding of my invention can be had, and the right is reserved by me to make such changes in the details of construction thereof which shall not depart from the spirit and scope of the appended claim.

Having thus described my invention, what I claim and desire to secure by Letters Patent is:—

In a portable conveyer tube, the combination of a section having an elongated opening formed therein, longitudinally extending angle irons fixedly mounted upon said section upon opposite sides of said opening, the outwardly extending walls of the angle irons extending in planes substantially at right-angles to each other, brackets fixedly mounted upon the inner surfaces of one wall of one angle iron, a door of substantially the same size as the opening in said section, angle bars fixedly mounted upon the outer surface of said door, one end of each angle bar being pivotally secured to said brackets, one edge of said door being bent outwardly at substantially right angles to form a longitudinally extending flange, the remaining ends of said angle bars abutting against the flange of said door for reinforcing the same, said flange of said door binding upon one of said angle irons when the door is swung forcibly to a closed position, by being reinforced by said angle bars, the angle bars also bearing directly upon said bracket and thus imparting a bearing strain directly to the remaining angle iron for relieving the securing elements of the bracket from direct strain, securing means passing through said flange and one of said angle irons for holding the door against ac-

cidentally opening, the remaining edge of the door fitting under said brackets for resisting upward movement, whereby said angle bars will reinforce the door for holding 5 the same against inward or outward urging action, thus forming a tight closure for the opening of said section.

In testimony whereof I affix my signature in presence of two witnesses.

THEODORE G. THORMODSON.
